United States Patent Office

Des. 193,447
Patented Aug. 21, 1962

193,447

DISPLAY BOX

Marvin W. Vannice, Burbank, Calif., assignor to Vue-Chest, Inc., Burbank, Calif., a corporation of California

Filed Nov. 22, 1960, Ser. No. 62,934

Term of patent 14 years

(Cl. D58—12.6)

FIG. 1.

FIG. 2.

FIG. 1 is a perspective view showing the front, top and one side of a display box embodying my new design; and

FIG. 2 is a perspective view showing the rear, top and other side thereof.

The dominant features of my design reside in the portions shown in full lines.

I claim:

The ornamental design for a display box, substantially as shown and described.
